US00D862587S

(12) **United States Design Patent** (10) Patent No.: **US D862,587 S**
(45) Date of Patent: ** Oct. 8, 2019

(54) **COUPLING FOR PROCESS CARTRIDGE
FOR IMAGE FORMING APPARATUS**

(71) Applicant: **CANON KABUSHIKI KAISHA**,
Tokyo (JP)

(72) Inventors: **Toru Oguma**, Shizuoka-ken (JP);
Naoya Asanuma, Shizuoka-ken (JP);
Tetsuya Numata, Shizuoka-ken (JP);
Takuya Kawakami, Shizuoka-ken (JP);
Yohei Kusano, Shizuoka-ken (JP);
Daisuke Hiramatsu, Tokyo (JP);
Takayuki Yada, Shizuoka-ken (JP);
Takatoshi Hamada, Shizuoka-ken (JP);
Go Torii, Shizuoka-ken (JP); **Hiroaki
Noshō**, Shizuoka-ken (JP)

(73) Assignee: **Canon Kabushiki Kaisha**, Tokyo (JP)

(**) Term: **15 Years**

(21) Appl. No.: **29/672,808**

(22) Filed: **Dec. 10, 2018**

Related U.S. Application Data

(62) Division of application No. 35/503,867, filed on Apr. 26, 2017 (U.S. filing date under 35 U.S.C. 384), and having an international filing date of Apr. 26, 2017.

(57) **CLAIM**

The ornamental design for a coupling for process cartridge for image forming apparatus, as shown and described.

DESCRIPTION

FIG. 1: Front view of a first embodiment

FIG. 2: Back view thereof

FIG. 3: Top view thereof

FIG. 4: Bottom view thereof

FIG. 5: Left view thereof

FIG. 6: Right view thereof

FIG. 7: Perspective view thereof

FIG. 8: Perspective view thereof

FIG. 9: Front view of a second embodiment

FIG. 10: Back view thereof

FIG. 11: Top view thereof

FIG. 12: Bottom view thereof

FIG. 13: Left view thereof

FIG. 14: Right view thereof

FIG. 15: Perspective view thereof; and,

FIG. 16: Perspective view thereof.

1 Claim, 16 Drawing Sheets
